UNITED STATES PATENT OFFICE.

GEORGES F. JACOT, OF LOCLE, SWITZERLAND.

WATCH-ESCAPEMENT.

SPECIFICATION forming part of Letters Patent No. 272,553, dated February 20, 1883.

Application filed October 13, 1882. (No model.)

To all whom it may concern:

Be it known that I, GEORGES FAVRE JACOT, of Locle, in the canton of Neufchatel, Republic of Switzerland, have invented certain new and useful Improvements in Watch-Escapements, of which the following is a specification.

In watch-movements with full plates it is difficult to connect the different parts of the movement which are arranged between the 10 main plates of the same, and it requires first-class workmen to put the movements together, and to repair the same, especially those parts which form the escapement.

The object of this invention is to facilitate 15 the assembling of the parts of the watch-movements described, and to furnish at the same time a better quality of movements.

The invention consists in arranging, in connection with the top plate of the movement, 20 an auxiliary bridge, which supports the lower ends of the arbors of the oscillating fork, escapement-wheel, and second-wheel, independently of the base-plate, the bridge being set into a recess of the base-plate, so that the 25 lower bearings of the different arbors, as well as the different wheels and pinions themselves, are supported in the same relative positions as heretofore.

In the accompanying drawings, Figure 1 30 represents a top view of a watch-movement with my improved escapement. Fig. 2 is a bottom view of the top plate with my improved escapement detached from the movement, and Fig. 3 is an end view of the movement as seen in the direction of the arrow, Fig. 1, and partly in section through the base-plate.

Similar letters of reference indicate corresponding parts.

40 Referring to the drawings, A represents the base-plate and B the top plate of a watch-movement with my improved escapement.

To the under side of the top plate B is secured an auxiliary bridge, C, which extends 45 in the direction of an imaginary line drawn through the arbors $b b' b^2$ of the fork d , escapement-wheel e , and second-wheel f of the movement sidewise of the small bridge D , which supports the lower end of the arbor of 50 the balance-wheel E . The bridge C is attached

by a thicker portion at one end to the top plate, B, and let into a recess, a , of the base-plate A in such a manner that the bearings of the different arbors, as well as the wheels and pinions on the same, are arranged exactly at 55 the same relative positions to the base and top plates as heretofore in watch-movements of this class, so that it is not necessary to make any change in the length of the different arbors.

The advantage of the auxiliary bridge C is 6c that the different parts of the escapement may be assembled and placed in position between the top plate B and bridge C independently of any connection with the base-plate, the top plate being then placed directly into position 65 on the base-plate without necessitating the difficult and time-consuming fitting of the arbors into the bearings of the base-plate, as 7c heretofore. Consequently the putting together of the movement, as well as the repairing of the same, is greatly facilitated, owing to the fact that all the parts which constitute the escapement are removed with the top plate from the base-plate of the movement, and can be 75 readily inspected, repaired, and put together again. Specially skilled workmen are therefore not required to put these movements together, and the repairing of watches of that class is also facilitated. My improved escapement is also adapted for the same reason for 80 three-quarter-plate movements.

Having thus described my invention, I claim as new and desire to secure by Letters Patent—

The combination, in a watch-escapement, of a top plate having an auxiliary bridge attached to its under side, said bridge supporting the arbors of the fork, escapement-wheel, and second-wheel, and a base-plate having a recess for the auxiliary bridge, so that all the parts of the escapement are supported in their 85 proper relative positions to the top and base plates, substantially as and for the purpose set forth.

In testimony that I claim the foregoing as my invention I have signed my name in presence 95 of two subscribing witnesses.

GEORGES FAVRE JACOT.
